UNITED STATES PATENT OFFICE.

ANDREW EPPLER, OF LYNN, MASSACHUSETTS, ASSIGNOR TO UNITED SHOE MACHINERY CORPORATION, OF PATERSON, NEW JERSEY, A CORPORATION OF NEW JERSEY.

SEWING MACHINE.

Application filed December 21, 1922. Serial No. 608,321.

The invention relates to machines for attaching welts or similar narrow strips to shoes, and more particularly to the means for treating the welt to facilitate its lateral 5 bendings about sharp contours such as the toe of a shoe sole.

While of more general application the invention has been developed and will be further described in connection with its application to an inseam sewing machine, such as is used for sewing together the welt, upper and insole of a welt shoe, for the purpose of slashing that portion of the welt only which is laid about the toe of the shoe. In 15 embodying the invention in a machine and mechanism of this character mechanism is provided for rendering the slashing devices active and inactive which is adjustable to vary the start of the welt slashing with relation to the throwing in of the mechanism. With this construction the mechanism may be uniformly rendered active upon starting the machine while the start of the slashing may be varied in accordance with the length 20 of the shoe to cause the slashed portion of the welt to register with the toe of the shoe being operated on. The interval which should elapse between the starting of the sewing and the starting of the welt slashing devices will depend upon the location of the slashing devices with relation to the stitch forming devices and also upon the length of the welt required to reach from the initial end of the seam to the toe. It is preferred 25 to locate the slashing devices at a distance in advance of the sewing point corresponding substantially to the length of welt which will reach from the initial end of the seam to the toe when operating on the shorter 30 shoes. In this case when operating on the shorter shoes the slashing will start with the sewing or immediately upon rendering active the mechanism which renders the slashing devices active and inactive. In operating 35 on longer shoes, however, the welt slashing will be delayed after this mechanism is rendered active for a period depending on the increased length of the shoe. The mechanism for rendering the slashing devices active and inactive is preferably so connected with the starting and stopping devices of the machine that it will be controlled therethrough and will, therefore, be thrown into and out of operation to cause the welt to be properly

slashed without any additional care or attention on the part of the operator. 55

The invention will be understood from the accompanying drawings in which Fig. 1 is a side elevation of an inseam sewing machine to which the preferred form of the invention has been applied, Fig. 2 is a side elevation partly in section of the welt slashing mechanism, Fig. 3 is an elevation looking toward the right in Fig. 2, Fig. 4 is a plan view of the welt slashing mechanism, Fig. 5 is a detail plan view of the welt slashing devices, Fig. 6 is a front elevation of the vertically movable welt supporting guide, Fig. 7 is a sectional view on line 7—7, Fig. 6, Fig. 8 is a rear elevation of the mechanism for rendering the welt slashing devices active and inactive looking toward the left in Fig. 1, and Fig. 9 is a sectional elevation on line 9—9, Fig. 8, looking toward the left. 60

In the drawings the invention is shown applied to the sewing machine for attaching a welt and upper to the sole of a welt shoe which is shown and described in Patent No. 1,260,521, March 26, 1918. This machine is provided with the usual stitch forming and work feeding devices including a hook needle 2, an awl 4, a channel guide 6, a looper 8, and a welt guide 10. The machine is provided with driving and stopping mechanism which may be the same in construction as 65 that shown and described in Patent No. 1,099,326, June 9, 1914, and is controlled from a treadle through the rod 12 as is usual in this type of machine. 70

The mechanism for treating the welt preliminary to its attachment to the shoe consists of welt slashing devices and a mechanism for rendering them active and inactive which when thrown into operation causes the welt slashing devices to slash the welt 75 during a pre-determined number of stitch forming and work feeding cycles and then to become inactive and to remain so until the mechanism is again thrown into operation. The welt slashing devices are arranged to 80 act on the welt between the welt guide 10 and the welt guiding and measuring roll 14 and at a distance from the sewing point substantially equal to the distance from the heel-breast, or point where the inseam begins, to the toe portion of the shortest shoes 85 which are to be sewed upon the machine. 90

The slashing devices comprise a slashing

knife 16 which is continuously reciprocated during the operation of the machine and a welt supporting slide 18 which is vertically movable to move the welt either into or out 5 of the path of the slashing knife. The knife is carried in a knife bar 20 provided on its upper face with a rack engaged by a spiral segment on the lower end of a lever 22, the upper end of which is connected by a link 24 10 with the rear end of the channel guide actuating lever 26 so that the knife is continuously reciprocated from the channel guide actuating cam 28 during the operation of the machine. The welt supporting slide 18 15 is provided with a support 30 which underlies the welt and with an overhanging arm 32 which overlies the welt and holds it on the support. The support may be vertically adjusted for different thicknesses of welt by 20 an adjusting screw 34, the upper end of which is held in engagement with a stud 36 on the slide 18 by a spring 38, the screw being clamped in adjusted position on the support by the bolt 40. The outer edge of the welt is 25 held in engagement with the face of the slide 18 by an edge guide 42 carried by the support 30 and laterally adjustable for different widths of welt by the adjusting screw 44. The welt is thus guided and held on the slide 30 18 so that it is moved into and out of the path of the slashing knife which cuts toward the outer edge of the welt and against the face of the slide.

The mechanism for raising and lowering 35 the welt supporting slide to render the welt slashing devices active and inactive comprises a cam 46 mounted on a fixed stud 48 at the back of the machine and engaging a roll at the upper end of a lever 50 which is secured 40 to the outer end of a rock shaft 52. The inner end of the rock shaft is provided with an arm 54 which is connected by a link 56 with a lever 58, the forward end of which is connected through toggle links 60 with the slide 18. 45 The lever 50 is held in engagement with the cam by the spring 62 acting on a collar 64 secured to the link 56, and back lash between the lower end of the link and the lever 58 is prevented by the spring 66 which holds the 50 pin 68 on the lever, through which the link passes, firmly in engagement with a collar 70 on the link. The position of the welt with relation to the slashing knife is, therefore, accurately controlled by the cam 46. When 55 the lever 50 is in engagement with the high part of the cam, as indicated in Fig. 1, the welt will be held in the path of the knife 16 so that the knife will act to slash the welt and when the lever rides off of the high part of the cam the welt will be lowered out of the path of the knife and the slashing of the welt will cease.

The mechanism for rotating the cam 46 is thrown into operation from the rod 12 in 60 starting the machine and comprises a ratchet

wheel 72 loosely mounted on the stud 48 and so connected with the cam 46 that the cam may be adjusted to vary the initial position of its high part with relation to the end of the lever 50. This connection, as shown, 70 comprises a pin 74 passing through a hole in the cam and held in engagement with one of a series of holes 76 in the ratchet wheel by a spring 78. The ratchet wheel is provided with a series of ratchet teeth somewhat longer than the high part of the cam 46 and with a concentric blank surface 80 beyond the teeth. The ratchet wheel is engaged by a pawl 82 secured to a rock shaft 84 in the outer end of a lever 86, the inner end of which carries 80 a roll 88 engaging the channel guide actuating cam 28 so that the pawl is continuously reciprocated during the operation of the machine. The rock shaft 84 is provided with a pawl controlling lever 90, one end of which is engaged by a spring 92 tending to hold the pawl in engagement with the ratchet wheel, and the other end of which is arranged to overlie an arm 94 secured to a shaft 96 which also carries a stop pawl 98 for engaging the 90 ratchet wheel and normally preventing the reverse rotation thereof. The initial or normal position of the ratchet wheel and cam 46 is determined by a stop 100 secured to the ratchet wheel and held in engagement with a fixed stop 102 by a spiral spring 104, one end of which is secured to the bearing for the stud 48, and the other end of which is secured to the ratchet wheel.

When the machine is started by depressing 100 the starting treadle and drawing the rod 12 downward the pawls 82 and 98 engage the teeth of the ratchet wheel and advance the ratchet wheel and cam 46 against the tension of the spring 104 until the pawl 82 rides onto the blank surface 80 when forward movement of the ratchet wheel and cam ceases and these parts are held stationary by the stop pawl 98. During this partial rotation of the ratchet wheel and cam the end of the lever 105 110 115 120 125 130 135 140 145 150 155 160 165 170 175 180 185 190 195 200 205 210 215 220 225 230 235 240 245 250 114 secured to the rod and engaging opposite sides of the arm. When the rod 12 rises upon the release of the treadle the arms 112 and 108 are rocked to raise the rod 106 so that its upper end lifts the arms 90 and 94, thus lifting the pawls 98 and 82 and disengaging them from the ratchet wheel so that it may return to initial position.

In operating upon the shorter shoes the cam 46 is adjusted as indicated in Fig. 1 so that the end of the lever 50 engages the forward end of the high part on the cam. With this adjustment the slashing of the welt begins when the machine is started and continues for a predetermined period determined by the length of the high part of the cam. In operating upon shoes which are considerably longer so that the slashed portion of the welt would not properly register with the toe of the shoe with the adjustment indicated in Fig. 1 the cam 46 is adjusted to shift the high part of the cam 46 with relation to the end of the lever 50 so that when the rotation of the cam is started in starting the machine the end of the lever will be in advance of the high part of the cam and will not be engaged by the cam to render the slashing devices active until the sewing and feeding of the welt has continued sufficiently to draw the extra length of welt past the slashing devices, after which the high part of the cam will engage the end of the lever 50 to start the slashing which will continue during the period measured by the length of the high part of the cam. When still longer shoes are to be sewed the cam 46 may be again shifted to increase the distance between the end of the lever 50 and the forward end of the cam 46 and thus increase the interval during which the slashing devices remain idle after the machine has been started and the cam and ratchet wheel rendered active. It has been found that three adjustments of the cam will take care of all sizes of shoes. The adjustment of the cam may be indicated by figures such as 3, 6 and 9 shown in Fig. 1 which by adjustment of the cam are brought into register with the upper end of a finger 116 secured to the end of the stud 48.

It is occasionally necessary, as for instance upon the breaking of the thread, to stop and re-start the machine during the sewing of a shoe. In such case the slashing devices should not be rendered operative in re-starting the machine and means is therefore provided through which the operator may render inoperative the mechanism for throwing the slashing devices into operation upon starting the machine. In the construction shown this means comprises the toggle levers 60 which connect the end of the lever 58 with the welt supporting slide 18. When these levers are straightened, as indicated in Fig. 2, the movements given to the lever 58 by the cam 46 are transmitted to the slide 18 as already de-

scribed. In case the operator wishes to render the mechanism inoperative he breaks the toggle formed by the levers 60 so that the movement of the lever 58 will not raise the welt into the path of the slashing knife. When the mechanism is to be again rendered active the toggle is returned to normal straightened condition. To enable the toggle links to be conveniently broken and straightened one of them is provided with a projecting handle 118.

While it is preferred to employ the specific construction and arrangement of parts shown and described in applying the invention to an inseam sewing machine of the type shown in the patent referred to it will be understood that this construction and arrangement is not essential to the broader features of the invention and may be varied or modified as found desirable or best suited to the construction and mode of operation of the machine to which it is to be applied.

What is claimed is:

1. A machine for attaching welts having, in combination, welt attaching mechanism, welt treating mechanism for operating on the welt for a limited period during the operation of the welt attaching mechanism, means controlled by the starting of the machine for rendering the welt treating mechanism active, and means for varying the start of the welt treating period with relation to the start of the welt attaching.

2. A machine for attaching welts having, in combination, welt attaching mechanism, welt treating devices, mechanism for causing said devices to treat the welt for a limited period during the welt attaching, means controlled by the starting of the machine for rendering the said latter mechanism active, and means for varying the start of the welt treatment with relation to the start of the welt attaching.

3. A machine for attaching welts having, in combination, welt attaching means, welt treating devices, and mechanism for causing said devices to treat the welt for a limited period during the welt attaching adjustable to vary the start of the welt treating with relation to the start of said mechanism.

4. A machine for attaching welts having, in combination, welt attaching means, welt treating devices, mechanism for causing said devices to treat the welt for a limited period during the welt attaching adjustable to vary the start of the welt treating with relation to the start of said mechanism, and means acting to render said mechanism active in starting the machine.

5. A machine for attaching welts having, in combination, welt attaching means, welt treating devices, and controlling mechanism therefor and means controlled by the starting of the machine for throwing said mech-

anism into operation and adjustable to vary the start of the welt treating with relation to the start of the welt attaching.

6. A machine for attaching welts to shoes having, in combination, welt attaching means, welt treating devices, mechanism for controlling said devices to treat the portion of the welt that is to be laid about the toe while the forward end of the welt is being attached having provision for adjustment to vary the start of the welt treating with relation to the start of the welt attaching and means controlled by the starting of the machine for throwing said mechanism into operation.

7. A machine for attaching welts to shoes having, in combination, welt attaching means, welt slashing devices, mechanism for causing the slashing devices to slash the portion of the welt which is to be laid about the toe of the shoe, means whereby the starting of the slashing with relation to the throwing into operation of said mechanism may be varied, and means for controlling the throwing into operation of said mechanism from the starting mechanism of the machine.

8. A welt sewing machine having, in combination, stitch forming devices, mechanism for slashing that portion of the welt which registers with the toe of the shoe, means controlled by the starting of the machine for throwing said mechanism into operation, and means whereby the start of the slashing may be varied in accordance with the length of welt between the initial end of the seam and the toe of the shoe to be operated upon.

9. A welt sewing machine having, in combination, stitch forming devices, welt slashing devices, and mechanism for causing said devices to slash a predetermined length of welt adjustable to vary the start of the slashing with relation to the throwing into operation of said mechanism.

10. A welt sewing machine having, in combination, stitch forming devices, welt slashing devices, mechanism for causing said slashing devices to slash a predetermined length of welt adjustable to vary the start of the slashing with relation to the throwing into operation of said mechanism, and means for throwing said mechanism into operation in starting the machine.

11. A welt sewing machine having, in combination, stitch forming devices, a reciprocating welt slashing knife in advance of the stitch forming devices, and means controlled by the starting of the machine for moving the welt into and out of the path of the knife to cause the welt to be slashed during certain stitch forming cycles and to remain unslashed during other stitch forming cycles.

12. A welt sewing machine having, in combination, stitch forming devices, means for slashing a welt in advance of the stitch forming devices comprising a reciprocating welt

slashing knife, and means controlled by the starting of the machine for relatively moving the welt and knife transversely of the plane of the welt into and out of effective operative position to cause the welt to be slashed during certain stitch forming cycles and to remain unslashed during other stitch forming cycles.

13. A welt sewing machine having, in combination, stitch forming devices, a reciprocating welt slashing knife in advance of the stitch forming devices, and mechanism acting when thrown into operation to move the welt into the path of the knife and out of said path after a predetermined period.

14. A machine for attaching welts having, in combination, welt attaching devices, welt treating mechanism acting when thrown into operation to treat the welt for a limited period during the operation of the welt attaching means, means controlled by the starting of the machine for throwing said mechanism into operation, and means under the control of the operator for permitting the machine to be started without throwing said mechanism into operation.

15. A machine for attaching welts having, in combination, welt attaching means, welt treating devices, a cam for rendering the said devices active and inactive, actuating means for the cam, and means for varying the initial position of the cam to vary the timing of the welt treating period with relation to the throwing into operation of the actuating means.

16. A machine for attaching welts having, in combination, welt attaching means, welt treating devices, means for actuating the welt treating devices, a timing cam for rendering said devices active and inactive to treat the welt for a limited period during the welt attaching, and actuating means for the cam thrown into operation in starting the machine.

17. A machine for attaching welts having, in combination, welt attaching means, welt treating devices, a timing cam for rendering said devices active and inactive to treat the welt for a limited period during the welt attaching, power operated actuating means for the cam thrown into operation in starting the machine, and means for varying the initial position of the cam.

18. A machine for attaching welts having, in combination, welt attaching means, welt treating devices, a cam for rendering said devices active and inactive to treat the welt for a limited period during the operation of the welt attaching means, power operated means rendered active in starting the machine for giving said cam a partial revolution only during the welt attaching operation, and means rendered active in stopping the machine for returning the cam to initial position.

19. A welt sewing machine having, in combination, stitch forming devices, means through which the operator controls the starting and stopping of the machine, welt slashing devices arranged to slash the welt in advance of the stitch forming devices, a cam for rendering said slashing devices active and inactive to slash the welt for a limited period during the sewing, and mechanism thrown into operation by said controlling means to advance the cam upon starting the machine and to return the cam to initial position upon stopping the machine.

ANDREW EPPLER.
